UNITED STATES PATENT OFFICE

HENRY W. ARMSTRONG, OF BRISTOL, CONNECTICUT, ASSIGNOR TO THE NATIONAL MARINE LAMP COMPANY, OF FORESTVILLE, CONNECTICUT, A CORPORATION OF CONNECTICUT

MARINE LAMP

Application filed May 5, 1928. Serial No. 275,328.

This invention relates to marine lamps, and more especially to running light lamps.

An object of the invention is to provide a lamp of this kind of the front closure class, in which the construction and organization are such as to be economical for manufacture and satisfactory for service and to render the lamp substantially proof against extinguishing of the light by wind entering around the closure. Another object is to provide simple and advantageous automatic means for holding the lens-carrying member shut, the means being of a character which enables the member to be unfastened and opened by one-hand operation in a single motion, and to be closed and fastened with similar facility.

In the accompanying drawings forming part hereof;

Fig. 1 is a front view of the lamp closed;

Fig. 2 is a horizontal section taken on the line 2—2 of Fig. 1;

Fig. 3 is a fragmentary horizontal section taken on the line 3—3 of Fig. 1;

Fig. 4 is a fragmentary vertical section taken on the line 4—4 of Fig. 1; and

Fig. 5 is a fragmentary elevation of the lamp with the hinged front open, the line of sight lying in the plane of the wall 3.

The lamp shown in the drawings is of the kind having a box body 2 which is of substantially sectoral shape in horizontal section, having two walls 3 and 4 approximately at right angles to each other and a curved front 5. The body has a bottom 6, and a customary domed top 7 surmounted by a ventilator cap 8. On the side wall 3 there is the usual socket 9 to receive the bracket on which the lamp is placed.

The interior of the curved front 5 is cut out to provide a door opening 10 through which the lamp 11 proper is accessible and removable.

In addition to the oil lamp, the body may be provided with a holder 12 for an electric light, as is common.

The front 5 affords a fairly wide face 13 which extends around the opening 10 at the sides and at top and bottom. At the top and at the bottom of the front, separated from the upper and lower edges of the door opening by the upper and lower portions of the face 13, are forwardly projecting flanges or ledges 14 and 15. These ledges may extend all the way around the body, and in themselves are a known constructional feature of such lamps, but they are here made use of for a particular purpose.

In accordance with the invention the lamp is provided with a hinged front 16, which constitutes a lens-carrying door but, instead of being large enough to cover the door opening with some degree of overlap, is coextensive with the fixed front 5 of the body. The hinged front is curved in a manner to conform substantially to the curvature of the fixed front, and is hinged at one side to the wall 3 of the body, the hinge as a whole being marked 17.

The hinged front 16 is made of sheet metal with its interior cut out to provide a lens opening 18. The lens opening is recessed inwardly in a familiar form, and the lens 19 is preferably held in the opening by retaining strips 20 which extend across the lens at top and bottom. Such retaining strips detachably secured at both ends by screws have long been known in the art. In the present lamp, however, these strips are hinged at one end so that they may not become separated from the part 16. At this end each strip is curled as shown at 21 to encircle a staple-like hinge member 22, the limbs of which pass through one of the side walls 23 of the recessed lens opening, to which the limbs are soldered on the inside. At the opposite ends of the strips I make use of the customary screw and nut fastenings 24, or of any other suitable form of detachable fastening. The hinged strips are not only safeguarded against loss, but

require the unfastening of only two fastenings in order to remove or insert a lens.

As stated, the hinged front 16 is coextensive with the fixed front 5. When closed, it extends from side to side, or from corner to corner, of the curved fixed front, and in the vertical direction from ledge 14 to ledge 15. Thus, not only by reason of the area of the surfaces in contact (that is to say, the entire 10 area of the face 13 and the corresponding area of the back of the hinged front), but also by reason of the close proximity of the upper and lower edges of the hinged front to the ledges, very effective protection is secured 15 against wind entering through the door opening and blowing out the light.

A further important wind protection is obtained by causing the hinged front to close or extend around one or both of the front corners of the body. This is particularly important 20 at the free edge of the hinged front, that is to say its edge or side remote from the hinge, and is important also at the hinged side.

At the hinged side this is contrived by disposing the hinge somewhat around the corner from the fixed front 5. The hinge preferably lies just in rear of the continuation of the curvature of the fixed front, though it will be understood that the result is not dependent upon exact relations and that the hinge might project somewhat forwardly of this curved line. The hinge is preferably made with hinge plates 25 soldered or otherwise secured to the outside of the wall 3 and having their forward edges 26 curled to receive a hinge pintle 27, the portions 26 and the pintle 27 being located approximately as stated. The hinge edge of the member 16 is cut out to receive the portions 26 of the hinge plates, and the other portions of this edge region are curled rearward at 28 to encircle the pintle.

At the free edge the hinged front is formed with a lip 29 bent rearwardly approximately 45 at a right angle. This lip extends from top to bottom of the hinged front or substantially so, and forms an effective joint-closing member which clasps against the outside of the wall 4.

The proportions are such that in order to engage the lip 29 over the corner of the body, and likewise to disengage it therefrom, it is necessary to force the moderately resilient material of which the member 16 is made, so 55 that the member is stretched or placed in tension. This draws the curved hinged front snugly against the curved fixed front, with something of a wrapping action, so that there is little opportunity for draft to pass between 60 the surfaces. The lip may also, and preferably does, act as an effective automatic catch for holding the hinged front closed.

Fig. 3 illustrates in an approximate manner the relations which exist when the hinged 65 front is about to be fully closed. The lip 29

is resting against the fixed front 5 adjacent the corner, or it may rest against the curve of this corner, which need not, of course, be perfectly square or sharp. A rearward, or a rearward and sideways push, on the knob 30 secured to this portion of the hinged front will force the lip over the corner and cause it to clasp the side of the body, where it is self holding; since the hinged front or the lip, or both, must be stretched or tensioned somewhat by a comparatively vigorous pull on the knob in order to draw the lip away from the corner.

For further security I may and preferably do also employ an automatic roller catch. Two of these are preferably provided, located above and below the horizontal center. The precise construction may be varied somewhat. As illustrated, each of these devices comprises a resiliently yielding plate 35 secured by screws and nuts 31, or in other suitable manner, to the side wall 4. The plate projects at the front beyond the lines of the fixed front 5 and is cut out to receive a roller 32, the plate being curled above and below the roller at 33 to engage and hold a pintle 34 on which the roller turns.

The roller is so positioned that it is encountered by the free edge of the member 16, and must be forced aside when the member is either opened or closed. In the closed position the roller engages over the edge of the member 16, hugging the front thereof. The lateral movement of the rollers is permitted by their resilient mountings.

These roller catches, while desirable, may be omitted, in which event reliance may be placed solely on the lip 29 as a catch. Naturally, if the roller catches are used, the engagement of the lip 29 with the body need not be so tight as it should be if the lip constituted the only catch. However, in order to secure the desired degree of tightness against wind it is advantageous to cause the lip to clasp around the corner quite firmly, and the presence of the two forms of catch gives double security that the door will not come upon accidentally.

I claim:

1. A marine lamp comprising a body of substantially sectoral section formed with a curved front comprising a face surrounding a door opening, and with forwardly projecting ledges extending across said front at top and bottom of said face, and a curved lens-carrying front hinged to said body and when closed lying against said face, said hinged lens-carrying front being substantially coextensive with the front of the body from corner to corner and from ledge to ledge, said hinged front having a substantially coextensive vertical lip at its free edge which closes around one corner of the body, and the hinge which connects the hinged front with the body being substantially coextensive with the

other vertical edge of the hinged front and being disposed to close around the other corner of the body.

2. A marine lamp comprising a body of substantially sectoral section formed with a curved front comprising a face surrounding a door opening, and with forwardly projecting ledges extending across said front at top and bottom of said face, and a curved lens-carrying front hinged to said body and when closed lying against said face, said hinged lens-carrying front being substantially coextensive with the front of the body from corner to corner and from ledge to ledge, said hinged front being constructed to close around both front corners of the body.
